COUPLER SHANK AND YOKE CONNECTION

William J. Metzger, East Cleveland, Ohio, assignor to National Malleable and Steel Castings Company, Cleveland, Ohio, a corporation of Ohio

Application November 1, 1944, Serial No. 561,367

7 Claims. (Cl. 213—72)

1

The invention relates to draft rigging for railway cars.

In my prior Patent No. 2,254,302 I have disclosed a coupler shank and yoke connection of a type in which the coupler may be angled both horizontally and vertically relative to the yoke. The construction shown in that patent is more particularly adapted for use on passenger cars. It is an object of my present invention to provide a coupler shank and yoke connection which will permit universal movement of the coupler, which will likewise possess other advantages inherent in the connection described in my patent aforesaid and which, additionally, will be adapted to certain limitations of freight car construction and service.

The standard sill spacing in freight cars is considerably less than in passenger cars, making it extremely difficult to obtain the requisite draft pin bearing area in a universal connection. Also, the space limitations between the forward end of the draft gear, or draft gear follower, and the end of the car brings the vertical pin connection of the rigging shown in my prior patent aforesaid so near the end of the car so as to make necessary the use of a coupler having a comparatively short shank, which, in turn, increases the degree of coupler angling for which provision must be made.

These are related problems in that less angling is possible with the closer sill spacing of freight cars. Also, reduction in coupler angling is very important from another aspect peculiar to freight train operation. This can best be illustrated by assuming a condition under which a heavy train of freight cars is being pushed over a cross-over or turnout and up a grade. Let us assume further a condition in which both tractor and pusher engines are employed, and in which the pusher must work continuously over the cross-over and up the grade. As the cars traverse the cross-over, they are angularly disposed to one another. When the cars reach the straightaway, they would again come into perfect alignment were the tractor engine alone to be considered, but with the pusher acting, this is not always the case. Rather, the cars may proceed up the grade on the straightaway with the couplers still in partly angled positions. This is undesirable as it leads to the imposition of a substantial lateral component of the pushing force, which under certain conditions will increase the likelihood of derailments, and which has other undesirable consequences. This condition is encountered more particularly in the case of radial or swivel butt couplers and is especially pronounced where both

2

vertical and horizontal pin connections are employed since this moves the vertical draft pin still farther toward the end of the car, and means an even shorter coupler shank with concomitant increase in angling. It is, therefore, a further important object of my invention to provide a universal coupler connection, which, within the limitations of existing freight car construction, makes it possible to use a coupler having a longer shank than is possible with the connection shown in my prior patent aforesaid. I have found that it is possible to accomplish this by a novel design of yoke connection which permits the horizontal draft pin to be brought closer to the forward end 15 of the draft gear or follower, and which further permits the vertical draft pin to be brought closer to the horizontal pin. Both of these things contribute to bringing the vertical pin closer to the forward end of the draft gear than has been possible heretofore.

In order to bring the horizontal draft pin farther back, I have found it desirable to decrease the thickness of the radial buffering block. This, in turn, has required strengthening the block, 25 which I have accomplished by providing lateral flanges extending over the sides of the radial connecting member. The provision of such flanges increases the width of the buffering block so that it cannot be inserted from the front of 30 the yoke. I have, however, devised a construction which permits insertion of the buffering block from the rear of the yoke head in such a way as to have an interlocking engagement with the head and so that, upon connection of the radial 35 draft member to the yoke, the buffering block is maintained in its interlocking relationship to the yoke head. These and other objects and advantages of the invention will appear more fully as the description proceeds.

40 In the drawings,

Fig. 1 is a vertical longitudinal sectional view of a preferred embodiment of my invention taken as indicated at 1—1 in Fig. 2. The view shows the forward or head end of the yoke, the radial draft member and the cooperating radial buffering block, the vertical draft pin being omitted.

Fig. 2 is a horizontal sectional view taken as indicated at 2—2 in Fig. 1; and Fig. 3 is a transverse vertical sectional view of the head of the 50 yoke taken as indicated at 3—3 in Fig. 1, the radial draft member and buffering block being omitted.

Figs. 4, 5, 6 and 7 are detail views of the buffering block, Fig. 4 being a rear view, Fig. 5 a side view, 55 Fig. 6 a front view, and Fig. 7 a perspective view.

The preferred construction illustrated is designed to be accommodated by the draft lugs of a freight car having standard center sill spacing. The yoke 10 may be of conventional construction except for its head end, which I will describe specifically. It is designed to receive a draft gear and to be mounted between the front and rear draft stops with the draft gear or its followers abutting thereagainst. Yoke 10 has an integral hollow head 11 of generally rectangular form, the forward portion of which is of restricted width inside as at w . This width is restricted by reason of the fact that the entire head of the yoke must be accommodated between draft stops attached to the sills while a certain minimum bearing area must be maintained between the draft pin 13 and opposed apertures 12 or between the pin and bushings 15 in said apertures.

A draft member 16 having a shank 17 arranged to be received between the lateral walls 18 of the hood 11 is provided with an aperture in line with the apertures 12 and may have a bushing 19 therein. The shank 17 of the draft member has a radial bearing surface 20 concentric with the draft pin aperture for engagement with a buffering block 21 having a complementary radial surface 22.

The buffering block 21, being of restricted depth, as shown in Fig. 1, is reinforced by lateral flanges 23, whose forward edges are curved in general alignment with the radial surface 22 of the block and which overlie the sides of the shank 17.

Recesses 24 are formed on the inside of the lateral walls 18, adjoining curved surfaces 25 formed on the inside of the head of the yoke. The curved surfaces 25 define the outside of bosses 26 surrounding the draft pin apertures 12. A small clearance is provided between surfaces 25 and the flanges 23 of the buffering block, as shown in Fig. 2.

It will be observed that the side walls 18 of the hollow head are of thinner cross-section rearwardly of the apertures 12 for the horizontal draft pin. This thinner section terminates forwardly in the cylindrical or radial surface 25 partly surrounding the rear of the draft pin apertures. The forwardly curved portions of the buffering block 21 extend forwardly of a transverse plane passing through the rear point of the apertures 12 in the head of the yoke. The recesses 24 in the head also extend forwardly of this transverse plane.

At each corner of the flat rear face 27 of the buffering block is provided a recess 28 having a vertical shoulder 29 which, when the parts are assembled, projects into one of the recesses 24 or behind one of the lugs 30 which defines the edges of the recesses 24 at each corner of the hood, holding the buffering block in interlocking engagement with the yoke.

I prefer that the lugs 30 be arranged at the corners of the hood so that the portions of the rear face 27 of the buffering block which lie between the recesses 28 may project between said lugs. This is illustrated both in Fig. 1 and in Fig. 2.

The surfaces which form the bottom of the recesses 28 in the buffering block extend away from the shoulders 29 at an angle which is designed to permit the buffering block to be inserted into the recesses 24 of the yoke from the rear thereof by first inserting one end of the block into said recesses and twisting the block to bring its other end into said recesses. This is illustrated by the dot-dash lines 21^a in Fig. 1. It will be observed that since the buffering block 21 is of a greater width than the restricted portion w of

the hood, it cannot be inserted from the forward end of the yoke. One of the important features of my invention resides in the construction which I have described in accordance with which the buffering block and yoke are so constructed and arranged that the block can be assembled by first inserting one end and then twisting or angling it into the position shown in full lines in Fig. 1. The first position is shown at 21^a. From this position it is swung about its upper end until the curved forward surfaces of the flanges 23 engage the radial surface 25 of boss 26 of the yoke, after which the block is rotated slightly to bring it into its final assembled position. Thereafter the draft member 16 is inserted into the yoke, and once the horizontal draft pin has been inserted, the buffering block can no longer be removed from the yoke.

A complementary feature to that which I have just described is that my construction enables the horizontal draft pin to be located farther to the rear than is possible, for example, in the construction disclosed in my prior Patent 2,254,302 referred to hereinabove. Another, and related, feature resides in arranging the connection between the draft member and the shank of the coupler, i. e. the center of the vertical draft pin aperture 31, close to the center line of the horizontal draft pin. For this purpose the forward end of the hood of the yoke is beveled interiorly as at 32, permitting the radial buffering surfaces 33 of the draft and buffering member 16 to be brought close to the apertures 12.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. In a draft rigging, a yoke having a hollow head, and a buffering block of greater width than the inside width of the forward portion of said hollow head, said buffering block having a curved forward side, recesses on the inside of said hollow head and adjoining curved surfaces formed on the inside of said head to accommodate the curved forward side of the buffering block, said buffering block being further constructed and arranged for assembly with said yoke by inserting one end of the buffering block into said recesses and twisting the block to bring its other end into said recesses.

2. In a draft rigging, a yoke having a hollow head, opposed apertures in the side walls of the hollow head to receive a draft pin, said side walls being of thinner cross-section rearwardly of said apertures than at said apertures to accommodate a buffering block having a curved forward side, the thinner section of said side walls terminating forwardly in cylindrical surfaces partly surrounding the rear of the draft pin apertures, and the curved forward side of the buffering block having lateral flanges extending into proximity with said cylindrical surfaces, said thinner section of the side walls forming recesses to hold the buffering block in assembled relationship with the yoke.

3. A draft rigging comprising a yoke, a radial draft member and a radial buffering block, said buffering block having a curved forward side and said yoke having a hollow head, opposed apertures in said head for a draft pin extending through the radial draft member, recesses on the

inside of said head for interlocking engagement with the buffing block and adjoining curved surfaces formed on the inside of said head to accommodate the curved forward side of the buffing block, the forward portion of said head being of lesser inside width than the buffing block, the yoke and buffing block being constructed and arranged for assembly by inserting one end of the block into said recesses and twisting the block to bring its other end into interlocking engagement with said recesses before assembly of the draft member with the yoke, and said yoke, buffing block and draft member being further constructed and arranged to prevent removal of the buffing block when the draft member is assembled with the yoke.

4. In a draft rigging, a yoke having a hollow head, retaining lugs extending inwardly from the walls of said hollow head rearwardly of its forward portion, a buffing block of greater width than said forward portion, said buffing block being insertable into interlocking engagement with said lugs, and a draft and buffing member having a shank mounted in the hollow head and cooperating with the buffing block to prevent its removal from interlocking engagement with said lugs, said buffing block having lateral flanges arranged to extend over the sides of said shank.

5. In a draft rigging, a yoke having a hollow head of generally rectangular form, a draft and buffing member having a shank of a width approximating the inside width of the forward portion of said yoke, a buffing block for cooperation with the shank of said draft member, said block having lateral flanges arranged to extend over the sides of said shank and into recesses formed on the inside of the lateral walls of said head, the buffing block being of greater width than the inside width of said forward portion of the head.

6. In a draft rigging, a yoke having a hollow head of generally rectangular form, a draft member extending into the forward portion of said hollow head, aligned circular apertures in the

lateral walls of the head and the shank of the draft member, said apertures in the lateral walls of the head being located in said forward portion of the head, recesses on the inside of said head extending forwardly of a transverse plane passing through the rear point of the apertures in the head, and a buffing block constructed and arranged for assembly with yoke by inserting one end of the block into said recesses and twisting the block to bring its other end into said recesses.

7. In a draft rigging, a yoke having a hollow head of generally rectangular form, a draft member extending into the forward portion of said hollow head, aligned circular apertures in the lateral walls of the head and the shank of the draft member, said apertures in the lateral walls of the head being located in said forward portion of the head, recesses on the inside of said head extending forwardly of a transverse plane

15 passing through the rear point of the apertures in the head, and a buffing block having a curved forward side for cooperation with the shank of the draft member, said buffing block being constructed and arranged for assembly with said yoke

20 by inserting one end of the buffing block into said recesses and twisting the block to bring its other end into said recesses so that the forwardly curved portions of the block are in interlocking engagement with the head of the yoke and extend forwardly of said plane.
